(57) **ABSTRACT**

A method of electrochemical reduction of carbon dioxide includes the use of multi-faceted Cu₂O crystals as a catalyst to convert CO₂ to value-added products. An electrochemical cell for the electrochemical reduction of carbon dioxide includes a cathode including the multi-faceted Cu₂O crystals. The multi-faceted Cu₂O crystals have at least two different types of facets with different Miller indices. The multi-faceted Cu₂O crystals include steps and kinks present at the transitions between the different types of facets. These steps and kinks improve the Faradaic Efficiency of the conversion of carbon dioxide. The multi-faceted Cu₂O crystals may be nanosized. The multi-faceted Cu₂O crystals may include 18-facet, 20-facet, and/or 50-facet Cu₂O crystals.

**SYNERGISTIC EFFECTS OF
MULTI-FACETED CU₂O NANOCRYSTALS
FOR ELECTROCHEMICAL CO₂
REDUCTION**

**CROSS REFERENCE TO RELATED
APPLICATION**

This application claims priority to U.S. Provisional Patent Application Ser. No. 62/811,708 filed Feb. 28, 2019, which is expressly incorporated herein by reference.

BACKGROUND

Cuprous oxide (Cu₂O; copper (I) oxide) is known to be one of the electro-catalysts capable of converting CO₂ to value-added products, by coupling with hydrogen in a process of electrochemical CO₂ reduction. However, Cu₂O in the form of single-faceted crystals is not an ideal catalyst for CO₂ conversion. A single-faceted crystal is referred to as a crystal particle in which the crystal lattice is continuous and unbroken to the edges of the crystal, with no grain boundaries, and the facets all having the same Miller index (i.e. the facets are all of the same type of facet).

Previous studies of CO₂ conversion have focused on single-faceted crystals of Cu₂O as a conversion catalyst. However, single-faceted Cu₂O crystals do not efficiently convert CO₂.

BRIEF DESCRIPTION

According to one aspect, a method of electrochemical reduction of carbon dioxide or carbonate ions (CO₃⁻²) includes providing an electrochemical cell including an anode, and a cathode including crystals of multi-faceted copper (I) oxide; introducing an aqueous medium containing carbon dioxide or CO₃⁻² into the cell; and reducing the carbon dioxide or CO₃⁻² by contacting the crystals with the aqueous medium while supplying electricity to the cell.

According to another aspect, electrochemical cell for the electrochemical reduction of carbon dioxide or carbonate ions includes an anode; a cathode including crystals of multi-faceted copper (I) oxide; an electrolyte arranged between the anode and the cathode; and an aqueous medium containing carbon dioxide or CO₃⁻² in contact with the cathode.

DETAILED DESCRIPTION

25 In order to improve the conversion efficiency of CO₂, multi-faceted Cu₂O crystals (e.g. nanocrystals) are proposed to be used as a catalyst for the reduction of CO₂ in an electrochemical cell. As used herein “multi-faceted” refers to crystals including facets having at least two different

30 Miller indices (i.e. having at least two different types of facets). In this invention, multi-faceted crystals of Cu₂O provide a synergistic effect when used in the conversion of CO₂ as compared to single-faceted crystal structures. The synergistic effect is produced by the steps and kinks between 35 facets of different types on the Cu₂O crystals, with the steps and kinks producing an increase in the Faradaic Efficiency in the conversion of CO₂ by electrochemical reduction to value-added products such as ethylene glycol, formic acid (HCOOH), methanol (CH₃OH), ethylene (C₂H₄), methane (CH₄), ethane (C₂H₆), ethanol, carbon monoxide (CO), acetic acid, acetone, other organic compounds, or combinations thereof.

40 Multi-faceted Cu₂O crystals may be more effective for the electrochemical reduction of CO₂ due to the presence of 45 these steps and kinks between the two different types of facets in the crystals. The steps and kinks are surface defects that arise in the transition between the two different types of facets in the crystals. These steps and kinks may provide more active sites for the electrochemical reduction of CO₂,

50 and may thus have more active sites compared to single-faceted crystals, which do not have transitions between different types of facets, but instead only have transitions between facets of the same type. Steps and kinks are surface defects, which may play an important role in the chemical

55 reactivity of the surface of the crystals. The advantages of the multi-faceted Cu₂O crystals is the presence of these steps and kinks, which may provide 1) more active sites than single-faceted Cu₂O single crystals alone; and 2) greater surface areas for electro-reduction, as compared with traditional single-faceted crystals, both of which may increase the Faradaic Efficiency in the conversion of CO₂ by electrochemical reduction as compared to single-faceted Cu₂O crystals.

60 In this invention, multi-faceted Cu₂O crystals are used as a catalyst for the electrochemical conversion of CO₂ to form an organic feedstock, including for example, formic acid, methanol, ethylene, methane, carbon monoxide, ethylene

glycol, acetic acid, ethanol, acetone, other hydrocarbons, other organic compounds, or combinations thereof.

The use of multi-faceted crystals as a catalyst for the reduction of CO₂, is not limited to such use, and these crystals may be used in other electrochemical reactions. Further, the use of multi-faceted crystals as a catalyst is not limited to the use of multi-faceted Cu₂O crystals, and can include the use of other multi-faceted particles including, for example, multi-faceted crystals of metals such as Cu, Ag, Au, Pt, Rh and Zn metals, metal alloys, and metal oxides as catalysts for the electrochemical reduction of CO₂ or other electrochemical conversions.

The conversion of CO₂ by electrochemical reduction may be performed using an electrochemical cell. The electrochemical cell may include an anode, a cathode including crystals of multi-faceted copper (I) oxide, an electrolyte arranged between the anode and the cathode, carbon dioxide or carbonate ions (CO₃⁻²) in contact with the cathode, and other known components. The carbon dioxide may be included (such as by bubbling) in an aqueous medium and introduced into the electrochemical cell in contact with the cathode. Alternatively, the aqueous medium may include CO₃⁻², which may be produced by dissolving carbon dioxide in a basic aqueous solution, such as aqueous sodium hydroxide. The carbon dioxide or CO₃⁻² may be introduced into electrochemical cell via the aqueous medium, and reduced by contacting the multi-faceted copper (I) oxide crystals with the aqueous medium while supplying electricity to the cell. The multi-faceted Cu₂O crystals may be arranged on a surface of the cathode so as to contact the aqueous medium.

By the electrochemical cell including the multi-faceted copper (I) oxide crystals in the cathode, the Faradaic Efficiency of CO₂ conversion by the electrochemical cell may be increased compared to electrochemical cells including cathodes having only single-faceted Cu₂O crystals.

The multi-faceted Cu₂O crystals may include two, three or more different types of facets. The multi-faceted crystals may have an average size (i.e. D50) of 10 nm to 5 μ m, 10 nm to 1 μ m, 10 nm to 500 nm, or 10 nm to 50 nm.

The multi-faceted Cu₂O crystals may be, for example, 18-facet Cu₂O crystals (FIGS. 5-8); 20-facet Cu₂O crystals (FIGS. 9-12); or crystals with other numbers of facets, e.g. 50-facet crystals (FIGS. 13-17), or combinations of two or more distinct populations of multi-faceted Cu₂O crystals (e.g. a combination of 18-facet, 20-facet crystals, and 50-facet crystals). The number of facets and the number of different types of facets in the crystals is not limited by the present subject matter. A ratio of copper to oxygen in the crystals may be from 3:1 to 1.9:1.

The 18-facet crystals may include (110) facets and (100) facets as seen in FIG. 6. The 18-facet crystals may include six square-shaped (100) facets, and twelve hexagonal-shaped (110) facets. A ratio of the (110) facets to the (100) facets may be from 2.1:1 to 1.9:1. A ratio of copper to oxygen in the 18-facet crystals may be from 2.4:1 to 2:1.

The 20-facet Cu₂O crystals may include (111) facets and (110) facets as seen in FIG. 10. The 20-facet crystals may include eight triangle-shaped (111) facets, and twelve elongated hexagon-shaped (110) facets. A ratio of the (110) facets to the (111) facets may be from 3.1:2 to 2.9:2. A ratio of copper to oxygen in the 20-facet crystals may be from 2.8:1 to 2.4:1.

The 50-facet Cu₂O crystals may include (100) facets, (111) facets, (110) facets and (311) facets as seen in FIG. 15. The 50-facet crystals may include six (100) facets, eight

(111) facets, twelve (110) facets and twenty-four (311) facets. A ratio of copper to oxygen in the 20-facet crystals may be from 2.8:1 to 2:1.

The multi-faceted Cu₂O crystals may have a high quality, which means that they are substantially uniform in shape, where substantially all (e.g. over 90%) of the crystals in a certain population include the same types of facets, and are free of other types of facets not shared by all the crystals in the particular population. By "substantially free" of other types of facets, it is meant that the crystals in a certain population include less than 5% by surface area of other types of facets not shared by all the crystals in the population. For the 18-facet crystals for example, these crystals may only include facets other than the (110) facets and the (100) facets at an amount less than 5% by surface area of the crystals. For the 20-facet crystals for example, these crystals may only include facets other than the (111) facets and the (110) facets at an amount less than 5% by surface area of the crystals.

The multi-faceted crystals may be produced by any reaction method, or may be naturally occurring. A reaction method may be performed at a predetermined temperature using a wet chemical process including a reaction mixture of raw materials.

The 18-facet Cu₂O crystals may be synthesized for example, by a method including forming a solution including a copper ion contributor dissolved in a solvent; adding a pH adjuster to the solution, wherein the solution has a pH of from 2-12; heating the solution to a first predetermined temperature of from 55-65° C. and agitated the solution until a precipitate forms in the solution; adding a reducing agent to the solution to thereby form a reaction mixture; and reacting the reaction mixture at a second predetermined temperature that is greater than the first predetermined temperature, and that ranges from 60° C. to 70° C., to thereby precipitate the 18-facet crystals from the reaction mixture.

The 20-facet Cu₂O crystals may be produced by a method including forming a solution including a copper ion contributor and a capping agent dissolved in a solvent; heating the solution to a predetermined temperature of from 95° C. to 105° C.; adding a pH adjuster to the solution; adding a reducing agent to the solution to thereby form a reaction mixture; and reacting the reaction mixture at the predetermined temperature to thereby precipitate the 20-facet crystals.

The solvent may be used to dissolve the other raw materials so that a wet chemical reaction can proceed between the reactants. The solvent may include any liquid capable of solubilizing the other raw materials, and can include tap or deionized water, aqueous ammonia solutions, or an organic solvent such as methanol, ethanol, acetone, ether, or glycerol for example. In one non-limiting embodiment, the solvent includes deionized water.

The copper ion contributor may be any substance that is capable of contributing copper ions (Cu²⁺), including for example, a copper salt or hydrate thereof. The copper salt can include for example copper (II) chloride (CuCl₂), copper (II) fluoride (CuF₂), copper (II) chloride (CuCl₂), copper (II) bromide (CuBr₂), copper (II) iodide (CuI₂), cuprous iodide (CuI), copper (II) oxide (CuO), copper (II) sulfide (CuS), copper (II) sulfate (CuSO₄), copper (II) nitride (Cu₃N₂), copper(II) nitrate (Cu(NO₃)₂), copper (II) phosphide (Cu₃P₂), copper (II) acetate (Cu(CH₃COO)₂), copper (II) hydroxide (CuOH)₂, copper(II) carbonate (CuCO₃), and copper (II) acetylacetone (Cu(C₅H₇O₂)₂), or combinations thereof. In some non-limiting examples, the copper ion

contributor includes one or more of copper (II) chloride dihydrate ($\text{CuCl}_2 \cdot 2\text{H}_2\text{O}$), copper (II) acetate hydrate ($\text{Cu}(\text{CH}_3\text{COO})_2 \cdot \text{H}_2\text{O}$), or copper (II) sulfate hydrate ($\text{CuSO}_4 \cdot 5\text{H}_2\text{O}$, cupric sulfate pentahydrate).

The copper ion contributor can be added to the solvent as a solid that is then dissolved therein. The amount of the copper ion contributor used in the reaction is not critical, and the copper ion contributor can be included at an amount to provide a molar concentration (i.e. molarity) in the reaction mixture of 1-40 millimoles (mmol) of copper ion contributor per liter (L) of reaction mixture, i.e. mmol/L or millimolar (mM). The copper ion contributor may also be included to provide a molar concentration of 5-15 mM, or 9-11 mM, or 10 mM in the reaction mixture. In one non-limiting example, the copper ion contributor is copper (II) acetate hydrate, and is included in an amount to provide a molar concentration of 36-37 mM in the reaction mixture to synthesize 18-facet Cu_2O crystals. In one non-limiting example, the copper ion contributor is cupric sulfate pentahydrate, and is included in an amount to provide a molar concentration of 9-10 mM in the reaction mixture to synthesize 20-facet Cu_2O crystals.

The materials used in synthesizing Cu_2O crystals may also include a capping agent, which is used to stabilize the crystals and control the crystal growth. The capping agent may include for example, polyvinylpyrrolidone (PVP), plant-derived extracts such as those from *Terminalia arjuna*, ethylene glycol, oleic acid, sodium laureth sulfate, sodium metaphosphate, oleylamine, dodecylbenzenesulfonic acid, ethylene diamine, triphenylphosphine oxide, peracetic acid, polyethylene glycol, fructose, tetramethylammonium hydroxide, and amino acids such as L-arginine.

The capping agent may be added to the solvent as a solid for dissolution therein. The amount of capping agent used in the reaction is not critical, and the capping agent can be included at an amount to provide a molar concentration of 0.01-150 mM, 10-100 mM, or 4-60 mM in the reaction mixture. In one non-limiting example, a capping agent is not used in the reaction mixture to synthesize 18-facet Cu_2O crystals. In another non-limiting example, the capping agent is oleic acid, and is included in an amount to provide a molar concentration of 120-125 mM in the reaction mixture to synthesize 20-facet Cu_2O crystals.

The materials used in synthesizing Cu_2O crystals may also include a pH adjustor, which can include various acids, bases, or combinations thereof, such as sodium hydroxide (NaOH) or ammonia for example. The pH adjustor may be used to adjust the pH of the reaction mixture to be between 2.0 and 12.0. The pH adjustor may be introduced as a solid for dissolution in the solvent, or as a solution, such as an aqueous solution after the pH adjustor has been dissolved in water. In one non-limiting example, the pH adjustor includes sodium hydroxide, which may be introduced as an aqueous solution having a molar concentration of sodium hydroxide in the reaction mixture of 10-1000 mM. In one non-limiting aspect, a sodium hydroxide aqueous solution is introduced in an amount to provide a molar concentration of 820-830 mM in the reaction mixture to synthesize 18-facet Cu_2O crystals. In another non-limiting aspect, a sodium hydroxide aqueous solution is introduced in an amount to provide a molar concentration of 70-80 mM in the reaction mixture to synthesize 20-facet Cu_2O crystals.

The materials used in synthesizing Cu_2O crystals may also include a reducing agent, which is included to donate electrons (by oxidation of the reducing agent) that are used for the reduction of the copper ions to produce Cu_2O crystals. The reducing agent may include for example, L-ascorbic acid (i.e. vitamin C, or $\text{C}_6\text{H}_8\text{O}_6$), hydrazine

monohydrate, sodium borohydride, hydrazine, 1,2-hexadecanediol, glucose, carbon monoxide, sulfur dioxide, iodides, hydrogen peroxide, oxalic acid, formic acid, carbon, reducing sugars, a borane compound, or combinations thereof.

The reducing agent may be added to the solvent as a solid for dissolution therein, or in a solution, such as an aqueous solution after the reducing agent has been dissolved in water. In one non-limiting example, the reducing agent is added to the solvent as a solution. The amount of the reducing agent used in the reaction is not critical and may be added to provide a molar concentration in the reaction mixture of 10-1000 mM, 20-500 mM, or 30-200 mM. In one non-limiting example, the reducing agent includes L-ascorbic acid, which may be introduced as an aqueous solution in an amount to provide a molar concentration of 20-40 mM in the reaction mixture to synthesize 18-facet Cu_2O crystals. In another non-limiting example, the reducing agent includes glucose, which may be introduced as an aqueous solution in an amount to provide a molar concentration of 160-180 mM in the reaction mixture to synthesize 20-facet Cu_2O crystals.

EXAMPLES

As inventive examples, three different multi-faceted Cu_2O crystals were prepared in order to demonstrate the synergistic effects of multi-faceted Cu_2O crystals in the electrochemical reduction of CO_2 for conversion. As a reference, a comparative example was prepared, including single-faceted crystals having 12-facets of the same type (110), such that the Cu_2O crystals are fully enclosed by twelve (110) facets.

Three inventive examples of multi-faceted Cu_2O crystals have been prepared, and include 18-facet Cu_2O crystals fully enclosed by 12 (110) facets and 6 (100) facets (referred to herein as "18-facet" crystals, see FIGS. 5-8), 20-facet Cu_2O crystals fully enclosed by 12 (110) facets and 8 (111) facets (referred to herein as "20-facet" crystals, see FIGS. 9-12), and 50-facet Cu_2O crystals by 6 (100), 8 (111), 12 (110) facets and 24 (311) facets (referred to herein as "50-facet" crystals, see FIGS. 13-17). As should be understood, the 18-facet, 20-facet, and 50-facet crystals are "multi-faceted" because they each have two or more distinct types of facets enclosing the crystals, and thus have steps and kinks in the transitions between the two different types of facets.

Example 1

An inventive example of 18-facet Cu_2O crystals was produced in accordance with the present subject matter. The 18-facet Cu_2O crystals of Example 1 were synthesized by dissolving 0.7 g of $\text{Cu}(\text{CH}_3\text{COO})_2 \cdot \text{H}_2\text{O}$ (copper ion contributor) in 70 ml of deionized water (solvent) in a 250 ml flask under constant electromagnetic stirring. The flask was kept in a 60° C. oil bath. 11.67 ml of 6.6 M NaOH aqueous solution (pH adjuster) was added dropwise into the above blue solution and kept stirring for 10 min. Once the NaOH was added, a precipitate formed and the solution gradually change in color to dark brown. Thereafter, 11.67 ml of 0.25 M vitamin C aqueous solution (reducing agent) was added to form a reaction mixture. The reaction mixture was heated to 65° C. for 12 min and a brownish-red product was produced. After the reaction time, the precipitate was separated from solution by centrifugation, washed with water and ethanol, and dried at 50° C. under vacuum for overnight. FIGS. 5-6 show SEM images of the 18-facet polyhedral Cu_2O crystals of Example 1. The crystal includes six square (100) facets and twelve hexagonal (110) facets, in which

both surfaces and edges developed well. FIG. 7 shows an EDS (energy dispersive spectroscopy) spectrum and FIG. 8 shows an EDS elemental mapping of the 18-facet polyhedral Cu_2O crystals of Example 1. The atomic percentage of Cu to O is a little more than 2 to 1 (Cu:O=69.8:30.2) as shown at the upper right of FIG. 7. The average size of the 18-facet Cu_2O crystals is approximately 1 μm , but this average size can be easily reduced to tens of nanometers.

Example 2

An inventive example of 20-facet truncated octahedral Cu_2O crystals was produced in accordance with the present subject matter. The 20-facet Cu_2O crystals of Example 2 were synthesized by dissolving 1.5 mmol of $\text{CuSO}_4 \cdot 5\text{H}_2\text{O}$ (copper ion contributor) in 60 ml deionized water (solvent) to form a light blue solution, followed by the addition of 30 ml ethanol (solvent) and 6 ml of oleic acid (capping agent) under vigorous stirring. The solution was heated to a temperature of 100° C., at which point 15 ml of sodium hydroxide aqueous solution (containing 12 mmol or 480 mg of NaOH) was added and stirred for 5-10 min. Finally, 45 ml of 0.6 M aqueous glucose solution (reducing agent) was added and stirred at 100° C. for 80 min. During the procedure, the color of the solution turned into light blue, dark blue and then brick-red. The resulting precipitate was collected by centrifugation and washed with ethanol 3 times and deionized H_2O twice to remove unreacted chemicals, and finally dried at 40° C. in a vacuum oven for 6 h.

FIGS. 9-10 show SEM images of the 20-facet truncated octahedral Cu_2O crystals of Example 2. The crystal includes eight (111) facets and twelve (110) facets, in which both surfaces and edges developed well. FIG. 11 shows an EDS (energy dispersive spectroscopy) spectrum and FIG. 12 shows an EDS elemental mapping of the 20-facet truncated octahedral Cu_2O crystals of Example 2. The atomic percentage of Cu to O is a little more than 3 to 1 (Cu:O=72.1:27.9) as shown at the upper right of FIG. 11. The average size of the 20-facet Cu_2O crystals is approximately 300 nm, but this average size can be easily reduced to tens of nanometers.

Cupric sulfate pentahydrate [$\text{CuSO}_4 \cdot 5\text{H}_2\text{O}$], oleic acid, D-(+)-glucose and sodium hydroxide were obtained from Sigma Aldrich. All of the chemicals were analytical grade and used without further purification.

Example 3

50-facet Cu_2O (FIGS. 13-17) crystals were made according to the present subject matter. FIG. 13-15 show SEM images of the crystals. FIG. 16 shows an EDS (energy dispersive spectroscopy) elemental mapping of the 50-facet Cu_2O crystals. FIG. 17 shows an EDS spectrum of the 50-facet Cu_2O crystals. The atomic percentage of Cu to O is a little more than 2 to 1 (Cu:O=69:31) as shown at the upper right of FIG. 17. The average size of the 50-facet Cu_2O crystals is approximately 2 μm , but this average size can be easily reduced to tens of nanometers.

Comparative Example 1

A comparative example of single-faceted Cu_2O crystals was produced to have twelve smooth facets of only a single type, i.e. only (110) facets. The 12-facet Cu_2O crystals of Comparative Example 1 were synthesized by dissolving 1.5 mmol of $\text{CuSO}_4 \cdot 5\text{H}_2\text{O}$ in 60 ml deionized water to form a light blue solution, followed by addition of 30 ml ethanol and 10.5 ml of oleic acid under vigorous stirring. The

solution was heated to 100° C., after which 15 ml of sodium hydroxide aqueous solution (12 mmol, 480 mg) was added to the above mixture and stirred for 5-10 min. Finally, 45 ml of 0.6 M aqueous glucose solution was added and stirred at 100° C. for 80 min. During the procedure, the color of the solution turned into light blue, dark blue and brick-red. The resulting precipitate was collected by centrifugation and washed with ethanol 3 times and de-ionized deionized H_2O twice to remove unreacted chemicals, and finally dried at 40° C. in a vacuum oven for 6 h.

FIGS. 1-3 show SEM images of the 12-facet rhombic dodecahedral Cu_2O crystals of Comparative Example 1. FIG. 4 shows an EDS (energy dispersive spectroscopy) spectrum of the 12-facet Cu_2O crystals of Comparative Example 1. The atomic percentage of Cu to O is a little more than 2 to 1 (Cu:O=68:32) as shown at the upper right of FIG. 4. The average size of the 12-facet Cu_2O crystals is approximately 1 μm .

The conversion efficiency of the Cu_2O crystals of the above examples were evaluated by including the Cu_2O crystals of the above examples separately in a cathode of an electrochemical cell. Carbon dioxide was in contact with the cathode and an electrical current was supplied to the cell to convert the CO_2 to value-added products.

One prominent feature of the electrochemical CO_2 reduction on Cu_2O is that ethylene glycol, one of value-added products for fuel, is used as an indicator. Table 1 below shows the Faradaic Efficiency (FE) for CO_2 reduction of these three different Cu_2O crystal examples for yielding various organic compounds as value-added products. Controlled potential coulometry experiments were conducted at -1.0V vs. Ag/AgCl for 1.5 h.

TABLE 1

	Faradaic Efficiency (FE) Cathode - Cu_2O Crystals				
	Formic Acid (%)	Ethylene Glycol (%)	Acetic Acid (%)	Ethanol (%)	Acetone (%)
Comparative Example 1: 12-facet	0.06	.0258	0.21	0.55	0.15
Example 1: 18-facet	0.68	11.28	0.15	1.66	0.31
Example 2: 20-facet	0.17	6.32	0.29	2.03	0.24
Example 3: 50-facet	0	32.67	3.03	0	7.84

As can be seen, the 18-facet, 20 facet, and 50 facet Cu_2O crystals, which are multi-faceted crystals including steps and kinks, have an FE of 11.28%, 6.32%, and 32.67%, respectively, for ethylene glycol production from the electrochemical reduction of CO_2 . These FE values are over 100 times the FE value of 0.0258% for the 12-facet crystals, which are single-faceted crystals with no steps and kinks.

Although all three example Cu_2O crystals include (110) facets, the multi-faceted crystals (18-facet and 20-facet crystals) having steps and kinks achieve a much higher electrochemical conversion of CO_2 than the single-faceted crystals of Comparative Example 1 due to the synergistic effects of steps and kinks of the multi-faceted Cu_2O crystals of Examples 1 and 2.

It will be appreciated that various of the above-disclosed and other features and functions, or alternatives or varieties thereof, may be desirably combined into many other different systems or applications. Also that various presently

unforeseen or unanticipated alternatives, modifications, variations or improvements therein may be subsequently made by those skilled in the art which are also intended to be encompassed by the following claims.

The invention claimed is:

1. A method of electrochemical reduction of carbon dioxide or CO_3^{2-} including:

providing an electrochemical cell including an anode, and a cathode including crystals of multi-faceted copper (I) oxide having facets with at least two different Miller indices and with steps and kinks between facets of different Miller indices;

introducing an aqueous medium containing carbon dioxide or CO_3^{2-} into the cell; and

reducing the carbon dioxide or CO_3^{2-} by contacting the crystals with the aqueous medium while supplying electricity to the cell;

wherein the crystals of multi-faceted copper (I) oxide include 18-facet crystals including (110) facets and (100) facets, 20-facet crystals including (111) facets and (110) facets, 50-facet crystals including (100) facets, (111) facets, (110) facets and (311) facets, or combinations thereof.

2. The method according to claim 1, wherein the carbon dioxide or CO_3^{2-} is reduced to an organic feedstock including formic acid, methanol, ethylene, methane, carbon monoxide, ethylene glycol, acetic acid, ethanol, ethane, carbon monoxide, acetic acid, acetone, or combinations thereof.

3. The method according to claim 1, wherein the crystals of multi-faceted copper (I) oxide include the 18-facet crystals including (110) facets and (100) facets.

4. The method according to claim 3, further including preparing the 18-facet crystals by:

forming a solution including a copper ion contributor dissolved in a solvent;

adding a pH adjuster to the solution, wherein the solution has a pH of from 2-12;

heating the solution to a first predetermined temperature of from 55-65° C. and agitated the solution until a precipitate forms in the solution;

adding a reducing agent to the solution to thereby form a reaction mixture; and

reacting the reaction mixture at a second predetermined temperature that is greater than the first predetermined temperature and ranges from 60° C. to 70° C., to thereby precipitate the 18-facet crystals from the reaction mixture.

5. The method according to claim 1, wherein the crystals of multi-faceted copper (I) oxide include the 20-facet crystals including (111) facets and (110) facets.

6. The method according to claim 5, further including preparing the 20-facet crystals by:

forming a solution including a copper ion contributor and a capping agent dissolved in a solvent;

heating the solution to a predetermined temperature of from 95° C. to 105° C.;

adding a pH adjuster to the solution;

adding a reducing agent to the solution to thereby form a reaction mixture; and

reacting the reaction mixture at the predetermined tem-

perature to thereby precipitate the 20-facet crystals.

7. The method according to claim 1, wherein the crystals have an average size of 10-500 nm.

8. The method according to claim 1, wherein the crystals of multi-faceted copper (I) oxide include the 50-facet crystals including (100) facets, (111) facets, (110) facets and (311) facets.

9. An electrochemical cell for electrochemical reduction of carbon dioxide or CO_3^{2-} including:

an anode;

a cathode including crystals of multi-faceted copper (I) oxide having facets with at least two different Miller indices and with steps and kinks between facets of different Miller indices;

an electrolyte arranged between the anode and the cathode; and

an aqueous medium containing carbon dioxide or CO_3^{2-} in contact with the cathode;

wherein the crystals of multi-faceted copper (I) oxide include 18-facet crystals including (110) facets and (100) facets, 20-facet crystals including (111) facets and (110) facets, 50-facet crystals including (100) facets, (111) facets, (110) facets and (311) facets, or combinations thereof.

10. The cell according to claim 9, wherein the crystals include the 18-facet crystals including (110) facets and (100) facets.

11. The cell according to claim 10, wherein a ratio of the (110) facets to the (100) facets is from 2.1:1 to 1.9:1.

12. The cell according to claim 11, wherein the crystals include facets other than the (110) facets and the (100) facets at an amount less than 5% by surface area of the crystals.

13. The cell according to claim 10, wherein:

a ratio of copper to oxygen in the crystals is from 2.35:1 to 2:1; and

an average size of the 18-facet crystals is 10 nm to 5 μm .

14. The cell according to claim 9, wherein:

the crystals include the 20-facet crystals including (110)

facets and (111) facets; and

a ratio of the (110) facets to the (111) facets is from 3.1:2

to 2.9:2.

15. The cell according to claim 14, wherein the crystals include facets other than the (110) facets and the (111) facets at an amount less than 5% by surface area of the crystals.

16. The cell according to claim 14, wherein:

a ratio of copper to oxygen in the crystals is from 2.6:1 to

2.3:1; and

an average size of the 20-facet crystals is 10 nm to 5 μm .

17. The cell according to claim 9, wherein the crystals include the 50-facet crystals including (100) facets, (110) facets, (111) facets, and (311) facets.

18. The cell according to claim 17, wherein the 50-facet crystals include six (100) facets, twelve (110) facets, eight (111) facets, and twenty four (311) facets.

19. The cell according to claim 18, wherein the crystals include facets other than the (100) facets, (110) facets, (111) facets, and (311) facets at an amount less than 5% by surface area of the crystals.

20. The cell according to claim 18, wherein:

a ratio of copper to oxygen in the crystals is from 2.8:1 to 2:1; and

an average size of the 50-facet crystals is 10 nm to 5 μm .
